[57] CLAIM

The ornamental design for a bicycle handlebar bar ends, as shown and described.

DESCRIPTION

FIG. 1 is a top view of a right bicycle handlebar bar end showing my new design.

FIG. 2 is a side view of the right bicycle handlebar bar end.

FIG. 3 is a bottom view of the right bicycle handlebar bar end.

FIG. 4 is a side view (opposite FIG. 2) of the right bicycle handlebar bar end.

FIG. 5 is a rear view of the right bicycle handlebar bar end.

FIG. 6 is a front view of the right bicycle handlebar bar end; and,

FIG. 7 is a perspective view of the right and left bicycle handlebar bar ends, the portions of the bicycle shown in broken lines are for illustrative purposes only and form no part of the claimed design.
